Primary Examiner—Robin Webster(74) *Attorney, Agent, or Firm*—Heslin Rothenberg Farley & Mesiti P.C.(57) **CLAIM**

The ornamental design for a sewage tank, as shown and described.

DESCRIPTION

FIG. 1 is a perspective view of a sewage tank in accordance with the new design;

FIG. 2 is a front elevational view thereof; a rear elevational view being a mirror image thereof;

FIG. 3 is a right side elevational view thereof; and,

FIG. 4 is a left side elevational view thereof.

The broken lines in the drawings are for illustrative purposes only and form no part of the claimed design.
